LEAD SALT OF DINITRO BENZOIC ACID AND
PRIMING COMPOSITION CONTAINING
THE SAMEWilli Brün, Bridgeport, Conn., assignor to Rem-
ington Arms Company, Inc., a corporation of
DelawareNo Drawing. Application October 19, 1931,
Serial No. 569,837

13 Claims. (Cl. 52—4)

This invention relates to certain new chemical compounds of a somewhat explosive nature, to the preparation of such compounds, and to their use either alone or in conjunction with other substances as explosive compositions, particularly as compositions for use as ammunition priming mixtures.

The compounds are derivatives of benzoic acid, particularly lead salts of 2-4 di-nitro benzoic acid. Two such lead salts have been discovered, and their analyses indicate compositions corresponding respectively to mono-basic lead 2-4 di-nitro benzoate and di-basic lead 2-4 di-nitro benzoate. The mono-basic salt is prepared as follows: A solution of 2.12 grams of 2-4 di-nitro benzoic acid and .8 grams of sodium hydroxide in 100 c. c. of water is dropped into a solution of 3.5 grams of lead nitrate in 100 c. c. of water, at a temperature between 70° and 80° C. The resulting precipitate is recovered by filtration and washing in the usual manner. It has a lead content of 49.07% which corresponds approximately to the theoretical lead content, 48.62%, of mono-basic lead 2-4 di-nitro benzoate, having the composition $C_{14}H_6N_4O_4Pb_2$ and the structural formula

The di-basic salt is prepared by dropping a solution of 2.12 grams of 2-4 di-nitro benzoic acid and 1.2 grams of sodium hydroxide in 100 c. c. of water into a solution of 5.25 grams of lead nitrate in 100 c. c. of water at a temperature between 70° and 80° C. The resulting precipitate has a lead content of 58.06%, corresponding quite closely to the theoretical lead content 57.80% of di-basic lead 2-4 di-nitro benzoate, having the composition $C_{14}H_6N_4O_4Pb_3$, and the structural formula

These salts are deficient in oxygen and of an explosive or semi-explosive character, and have been found to be highly useful as ingredients of ammunition priming mixtures, in which they are

best used as fuel ingredients. Their utility is enhanced by their explosive character, as distinguished from the non-explosive character of the priming mixture fuels hitherto used.

One example of a priming mixture including a basic lead salt of 2-4 di-nitro benzoic acid is the following:

Mercury fulminate	30% to 50%
Barium nitrate	20% to 40%
Mono-basic or di-basic lead 2-4 di-nitro benzoate	5% to 15%
Abrasive	approximately 20%

When such a mixture is prepared wet, a small percentage of a suitable binder may be added. This formula, however, is merely typical. The explosive, mercury fulminate, may be replaced wholly or in part by a nitro organic compound, such as a lead salt of styphnic acid, or such a salt in admixture with guanylnitrosaminoguananyl-tetracene, lead methylene di-iso nitro amine, diazo-di-nitro phenol, a lead salt of picric acid, and similar explosive bodies. Suitable non-corrosive oxidizers include other nitrates, such as normal or basic lead nitrate, chromates, permanganates, oxides and peroxides. Other fuels, such as lead sulphocyanate, antimony sulphide and/or calcium silicide, may likewise be used in conjunction with the lead salts of 2-4 di-nitro benzoic acid. The said lead salts being themselves novel, the appended claims are to be broadly construed.

What is claimed is:

- As a composition of matter, a lead salt of 2-4 di-nitro benzoic acid.
- As a composition of matter, a basic lead salt of 2-4 di-nitro benzoic acid.
- As a composition of matter, mono-basic lead 2-4 di-nitro benzoate.
- As a composition of matter, di-basic lead 2-4 di-nitro benzoate.
- A priming composition containing a lead salt of 2-4 di-nitro benzoic acid.
- A priming composition containing a basic lead salt of 2-4 di-nitro benzoic acid.
- A priming composition containing mono-basic lead 2-4 di-nitro benzoate.
- A priming composition containing di-basic lead 2-4 di-nitro benzoate.
- A priming composition containing a lead salt of 2-4 di-nitro benzoic acid, a suitable combustion initiator, and a suitable oxidizer.
- A priming composition containing a basic lead salt of 2-4 di-nitro benzoic acid, a suitable combustion initiator, and a suitable oxidizer.

11. The method of making lead salts of 2-4 di-nitro benzoic acid which comprises the addition to an aqueous solution of lead nitrate of an aqueous solution of sodium hydroxide and 2-4 di-nitro benzoic acid.
- 5 12. The method of making mono-basic lead 2-4 di-nitro benzoate which comprises precipitating said salt by the addition to a solution of 3.5 grams of lead nitrate in 100 c. c. of water of 10 a solution of 2.12 grams of 2-4 di-nitro benzoic acid and .8 grams of sodium hydroxide in 100 c. c. of water at a temperature between 70° and 80° C.
13. The method of making di-basic lead 2-4 di-nitro benzoate which comprises precipitating said salt by the addition to a solution of 5.25 grams of lead nitrate in 100 c. c. of water of a solution of 2.12 grams of 2-4 di-nitro benzoic acid and 1.2 grams of sodium hydroxide in 100 c. c. of water at a temperature between 70° and 80° C.

WILLI BRÜN.
